UNITED STATES PATENT OFFICE

LEO L. BUCK, OF PITTSBURGH, PENNSYLVANIA, ASSIGNOR TO THE UNION SWITCH & SIGNAL COMPANY, OF SWISSVALE, PENNSYLVANIA, A CORPORATION OF PENNSYLVANIA

RAILWAY BRAKE-CONTROLLING APPARATUS

Application filed February 21, 1930. Serial No. 430,292.

My invention relates to railway brake controlling apparatus, and particularly to apparatus of the type involving means for causing an automatic brake application when a train enters a caution block, together with means for restraining or preventing such automatic application if the engineman operates his brake valve in such manner as to cause a manual application of the brakes.

Heretofore the customary practice has been to make the automatic brake application a service application, but on some railroads the block lengths are such that a service application must occur immediately upon entering the block in order to reduce a train from full speed to stop at the end of the block. In such instances it is impractical to use a service application for an automatic application of the brakes, because a certain delay period is necessary within which the engineer may apply the brakes manually, thereby preventing the automatic application, and such delay period plus service braking distance will exceed the block length. One feature of my invention is the provision of means operating to cause an emergency brake application after the lapse of a fixed time interval following the entrance of a train into a caution block, the fixed time interval plus maximum emergency braking distance being substantially equal to the block length.

I will describe one form of apparatus embodying my invention, and will then point out the novel features thereof in claims.

In the accompanying drawing, Fig. 1 is a diagrammatic view showing one form of apparatus embodying my invention. Fig. 2 is a view showing by means of curves one manner of utilizing the apparatus illustrated in Fig. 1.

Referring first to Fig. 2, the reference character T designates a railway track along which traffic normally moves in the direction indicated by the arrow, which track is divided by insulated joints 8 to form a plurality of blocks, of which only one block G—H is shown in the drawing. These blocks are of such length that if a train enters a block at full speed, which I will assume to be 60 miles per hour, and if a service application occurs

at the moment the train enters the block, the train will be brought to a full stop just before reaching the exit end of the block. This is illustrated in Fig. 2 by the curve Y, it being assumed that a manual service application of the brakes occurs at the point Y¹. Under these conditions the train will be brought to a stop at point Y², which is about 200 ft. in the rear of the exit end of the block. The effect of an emergency application of the brakes is represented by the curve X. If this application occurs at the point X¹, which is about 750 ft. from the entrance end of the block, and if the train is traveling at 60 miles per hour when the application occurs, the train will be brought to a stop at substantially point Y², that is, at substantially the same point as before. A train traveling at 60 miles per hour will consume approximately 9 seconds in covering 750 ft., and so the emergency application of the brakes may be delayed about 9 seconds after the train enters the block and the train will still be brought to a stop before leaving the block.

Referring now to Fig. 1, the reference character R designates a relay which is controlled from the trackway in such manner that the relay is energized under safe traffic conditions, but becomes deenergized when the train enters a caution block. The apparatus for controlling this relay forms no part of my present invention, and, consequently, it is omitted from the drawing. A magnet K is controlled by front contacts 6 and 7 of relay R, with the result that this magnet is energized or deenergized according as the relay is energized or deenergized. Magnet K controls a valve F, which valve in turn controls the supply of fluid pressure to two reservoirs A and B. When the valve F is in the position shown, that is, when magnet K is energized, reservoir A is connected with a source of fluid pressure through pipes 9 and 2, and reservoir B is disconnected from both reservoir A and the source of pressure. When magnet K becomes deenergized, valve F will reverse, thereby disconnecting reservoir A from the source of pressure and connecting this reservoir with reservoir B through a restricted orifice C and a pipe 3. The condi-

tion which will then exist is determined by the position of the engineer's brake valve M. If this valve is in the release, running, holding or lap position, reservoir B will be connected with atmosphere through a pipe 4, a port 10 in the engineer's brake valve M, a pipe 5 and a whistle W. Under this condition, the pressure in reservoir A will gradually reduce to atmospheric value through the restricted orifice C. If, on the other hand, the engineer's brake valve M is in the service or the emergency position, pipe 4 will be blanked, and under this condition the air in reservoir A will gradually be reduced to an intermediate value determined by the equalization pressure of reservoirs A and B.

The reference character D designates a pressure responsive device which is connected with reservoir A through a pipe 1, and which in turn controls a valve E. The pressure responsive device D comprises a cylinder 15 containing a piston 11 which is biased upwardly by a spring 12. When the pressure in reservoir A is above the intermediate value referred to hereinbefore, this pressure overbalances the effect of spring 12 and the piston 11 occupies the position in which it is shown in the drawing. When the pressure in reservoir A drops below this intermediate value, piston 11 will rise and will therefore reverse the position of the valve member 13 in valve E. When valve member 13 occupies the position in which it is shown in the drawing, the brake pipe is closed, but when this valve member rises, the brake pipe becomes directly connected with atmosphere through an exhaust port 14 and this will result in an emergency application of the brakes.

Assuming that reservoir B is connected with atmosphere when magnet K becomes deenergized, the parts are so proportioned and adjusted that a period of about 9 seconds will elapse before valve E will reverse to cause the emergency application of the brakes.

Reverting now to Fig. 2, I will assume that a train equipped with the apparatus shown in Fig. 1 passes caution signal S^c at 60 miles per hour. If the engineer moves his brake valve to the service position at point Y^1 , that is, immediately upon passing signal S^c , the train will be brought to a stop at point Y^2 , and the operation of the emergency brake valve E will be prevented. If, however, the engineer takes no action in response to the caution indication given by signal S^c , brake valve E will reverse at approximately X^1 , with the result that the train will be brought to a stop at the same point, namely, point Y^2 .

Although I have herein shown and described only one form of apparatus embodying my invention, it is understood that various changes and modifications may be made therein within the scope of the appended

claims without departing from the spirit and scope of my invention.

Having thus described my invention, what I claim is:

1. Train-carried apparatus for an automatic train control system, comprising a magnet controlled from the trackway in such manner as to be energized under safe traffic conditions and to become deenergized when the train enters a caution block, two reservoirs A and B, a source of fluid pressure; a valve device so controlled by said magnet that when the magnet is energized reservoir A is connected with said source of fluid pressure but reservoir B is disconnected from the source and from reservoir A, whereas when the magnet becomes deenergized reservoir A is disconnected from said source and is connected with reservoir B through a restricted orifice; a port associated with the usual engineer's brake valve for connecting reservoir B with atmosphere at all times except when such valve is in the service or emergency position; whereby when said magnet becomes deenergized the pressure in reservoir A will gradually drop to an intermediate pressure or to atmospheric pressure according as the engineer's valve is or is not in a brake-applying position, and a valve responsive to the pressure in reservoir A and operating to cause an emergency application of the brakes when the pressure in reservoir A drops below said intermediate value.

2. Railway traffic controlling apparatus comprising a track divided into blocks of such lengths that substantially an entire block is required to reduce a train from full speed to a stop by a service brake application, a train-carried magnet so controlled from the trackway as to be energized under safe traffic conditions and to become deenergized when the train enters a caution block, two reservoirs A and B, a source of fluid pressure; a valve device so controlled by said magnet that when the magnet is energized reservoir A is connected with said source of fluid pressure but reservoir B is disconnected from the source and from reservoir A, whereas when the magnet becomes deenergized reservoir A is disconnected from said source and is connected with reservoir B through a restricted orifice; a port associated with the usual engineer's brake valve for connecting reservoir B with atmosphere at all times except when such valve is in the service or emergency position; whereby when said magnet becomes deenergized the pressure in reservoir A will gradually drop to an intermediate pressure or to atmospheric pressure according as the engineer's valve is or is not in a brake-applying position, and a valve responsive to the pressure in reservoir A and operating to cause an emergency application of the brakes when the pressure in reservoir A drops below said intermediate value,

the time interval required

for the pressure in reservoir A to drop below said intermediate value being such that the resulting emergency brake application will reduce the train from full speed to a stop at substantially the end of the caution block.

5 In testimony whereof I affix my signature.

LEO L. BUCK.
